COPYHOLDER

Cash Wayne Edwards, New York, N. Y.

Application March 4, 1940, Serial No. 322,218

4 Claims. (Cl. 120—29)

This invention relates to copyholders of the type generally employed by typists and the like for holding manuscripts and other work while making typewritten copies thereof; and an object 5 of the present invention as to provide a copyholder that is characterized by simplicity of construction, fewness of parts and yet will be found efficient for the purpose designed.

The invention, together with its objects and 10 advantages, will be best understood from a study of the following description taken in connection with the accompanying drawings wherein:

Figure 1 is a front elevational view of the copyholder.

15 Figure 2 is a rear elevational view thereof.

Figure 3 is a vertical sectional view taken substantially on the line 3—3 of Figure 2.

Figure 4 is a horizontal sectional view taken substantially on the line 4—4 of Figure 1.

20 Referring more in detail to the drawings it will be seen that in the preferred embodiment thereof the copyholder comprises a panel 5 of metal or other suitable material having an integral marginal flange 6 and supported in a vertical position through the medium of legs 7.

The legs 7 are adjustably connected to the panel so that the panel may be raised or lowered to the desired elevation, and in this connection it will be noted that the legs 7 are equipped with 30 threaded shanks 8 that extend through openings provided therefor in the bottom section of the flange 6 and are equipped with pairs of lock nuts 9 to be threaded home against said lower section of the flange 6 in securing the legs to the panel 35 and the panel at the desired position of adjustment.

Also, the legs 7 have resilient surface-contacting elements 10 associated therewith so that in using the device the desk, table, or the like will 40 not be scarred as a result of such use.

45 Rotatably supported between the vertical sections of the flange 6 at the rear or hollow side of the panel, and adjacent the upper edge of the panel is a shaft 11 on which is mounted, for rotation therewith, a paper feed roll 12 having a periphery of rubber or other material that will have good frictional contact with the paper or manuscript for feeding the latter vertically of the panel 6.

50 The roller 12 is disposed opposite a slot 13 elongated transversely of the panel adjacent the upper edge thereof and the periphery of the roller 12 projects through the slot for contact with the paper or manuscript.

55 For yieldably holding such paper or manuscript

against the periphery of the feed roll 12, there is pivotally mounted on the panel 5 to extend across the front side of the panel a bail 14.

The bail 14 has the legs thereof terminating in pintles 15 journaled in suitable openings provided therefor in the vertical sections of the flange 6, and engaged with the pintles 15 are coil springs 16 that are anchored at the rear side of the panel and to the vertical sections of the flange 6 as at 17.

10 Mounted on the bight of the bail 14 for rotation relative thereto, if desired, or held thereon stationary relative to the bail, are contact rolls 18 that serve to maintain the paper or manuscript in proper contact with the periphery of the feed roll 12. In this connection it will be appreciated that the springs 16 bias the bail 14 in a manner to engage the rolls 18 with the paper or manuscript and maintain such paper or manuscript in contact with the peripheries of the rolls 18 and the feed roller 12.

15 For operating the feed roller 12 there is provided an operating shaft 19, one end of which is rotatably supported at a lower corner of the panel 5 and the opposite end of which is journaled in the vertical section 20 of a bracket 21 that extends forwardly from the panel 5 and at one end is secured to the panel as at 22, and as best shown in Figures 1 and 3.

20 At the lower end thereof the vertical section of the bracket 21 is equipped with a surface contact element 23 of rubber or other suitable material.

On the outer end thereof the shaft 19 is equipped with a handle 19', while at the other end thereof the shaft 19 is in driving engagement with the shaft 11 of roller 12 through the medium of a chain and sprocket drive connection 24 disposed at the rear side of the panel 5 and within the confines of the flange 6 and as clearly shown in Figures 2 and 3.

25 To maintain the runs of the chain of the drive connection 24 out of contact with the panel 5, there is provided on the rear side of the panel 5 at a point where the runs of the chain cross, a sound-absorbing element 25 as shown in Figure 2.

30 From the above it will be apparent that with the paper or manuscript disposed between the roller 12 and rolls 18 the operator by turning the knob 19' will cause the roller 12 to rotate for feeding the paper.

35 To assist the typist or copyist in following the work to be copied, line by line, there is provided an index or line finder 26. The same is in the nature of a rod disposed transversely of the panel 5 at the front side of the panel and terminating

45

50

55

55

at its opposite ends in pintles 27 suitably journaled in the vertical sections of the flange 6 and threaded to accommodate pairs of lock nuts 28 through the medium of which the line finder or 5 index rod 26 is secured against free vertical swinging movement, while at the same time the said line finder or index rod 26 may be adjusted relative to the front face of the panel 5 as required by the thickness of the paper or manuscript to be copied.

Obviously in using the device, the paper or manuscript bearing the data to be copied is disposed vertically at the front side of the panel 5 with a portion thereof placed between the peripheries of the roller 12 and rolls 18, and the index or line finder rod 26 disposed transversely of the copy work.

The copyholder will be disposed at a position convenient to the typist, and when disposed at 20 the back of the typewriter in front of the typist the rod 19 will extend forwardly and preferably is of such a length as to have the knob 19' thereof disposed convenient to the keyboard of the typewriter to be readily grasped by the hand of 25 the typist for rotating the rod 19 to cause, in a manner hereinbefore described in detail, a shifting of the paper vertically relative to the panel 5 of the copyholder and in an up or down direction as desired in the course of making a copy 30 or copies of the work.

It is thought that a clear understanding of the construction, utility, manner of use, and advantages of a copyholder embodying the features of the present invention will be had without 35 a more detailed description.

Having thus described the invention what is claimed as new is:

1. In a copyholder of the character described, a panel having a continuous marginal flange, 40 supporting legs for the panel adjustably secured to a section of the flange at the bottom of the panel for supporting the panel perpendicularly when in use, a roller rotatably supported between the vertical sections of said flange at the rear 45 side of the panel and adjacent the upper edge of the panel, said panel in the region of said roller being provided with a slot elongated transversely thereof and through which the periphery of the roller projects towards the front of the 50 panel, a bail pivotally mounted on the panel adjacent the upper end thereof, rolls on said bail for contact with the manuscript for yieldably urging the latter into frictional contact with the periphery of said roller, an operating shaft for 55 said roller extending forwardly from said panel adjacent the lower corner of the panel, and an endless chain mechanism connecting said shaft in driving engagement with said roller for rotating the latter to feed the work relative to the 60 panel, and a line guide mounted on the panel and extending transversely thereof.

2. In a copyholder of the character described, a panel having a continuous marginal flange, 65 supporting legs for the panel adjustably secured to a section of the flange at the bottom of the panel for supporting the panel perpendicularly when in use, a roller rotatably supported between the vertical sections of said flange at the rear side of the panel and adjacent the upper edge 70 of the panel, said panel in the region of said roller being provided with a slot elongated transversely thereof and through which the periphery of the roller projects towards the front of the panel, a bail pivotally mounted on the panel adjacent the upper end thereof, rolls on said bail

for contact with the manuscript for yieldably urging the latter into frictional contact with the periphery of said roller, an operating shaft for said roller extending forwardly from said panel adjacent the lower corner of the panel, and an endless chain mechanism connecting said shaft in driving engagement with said roller for rotating the latter to feed the work relative to the panel, and a line guide mounted on the panel and extending transversely thereof, and means 10 securing said line guide to the panel at the flanged side edges thereof, and for securing said line guide in stationary adjusted position relative to the panel to accommodate copy work of varying thicknesses.

3. In a copyholder of the character described, a panel having a continuous marginal flange, supporting legs for the panel adjustably secured to a section of the flange at the bottom of the panel for supporting the panel perpendicularly 20 when in use, a roller rotatably supported between the vertical sections of said flange at the rear side of the panel and adjacent the upper edge of the panel, said panel in the region of said roller being provided with a slot elongated transversely thereof and through which the periphery of the roller projects towards the front of the panel, a bail pivotally mounted on the panel adjacent the upper end thereof, rolls on said bail for contact with the manuscript for yieldably 25 urging the latter into frictional contact with the periphery of said roller, an operating shaft for said roller extending forwardly from said panel adjacent the lower corner of the panel, and an endless chain mechanism connecting said shaft in driving engagement with said roller for rotating the latter to feed the work relative to the panel, and a line guide mounted on the panel and extending transversely thereof, and means 30 securing said line guide to the panel at the flanged side edges thereof, and for securing said line guide in stationary adjusted position relative to the panel to accommodate copy work of varying thicknesses, and spring means anchored to the panel at the rear side thereof and connected with said bail for yieldably urging the bail and the rolls thereon toward said roller for effectively retaining the copy work in contact with said roller.

4. In a copyholder of the character described, a panel, means connected with the panel for supporting the same perpendicularly, said panel having a transversely arranged slot in its top portion, a roller carrying shaft supported for rotary movement in rear of the panel with the 55 roller projecting through the slot, a bail extending across the front face of the panel and across the slot and having its end parts rotatably supported at the rear of the panel, friction rollers carried by the bail for holding a sheet against the first-mentioned roller, spring means for pressing the rollers of the bail against said sheet, means for actuating the roller carrying shaft and a line guide extending across the front of the panel, said operating means for the shaft comprising a forwardly extending shaft having one end journaled in a lower corner of the panel, a bracket connected with the panel and extending forwardly and forming a bearing for an intermediate part of the forwardly extending shaft, 70 a handle connected with the forward end of the forwardly extending shaft and chain and sprocket means connecting the rear end of the forwardly extending shaft with the roller carrying shaft.
